Primary Examiner — Catherine S Posthauer

(57) **CLAIM**

The ornamental design for a battery tray, as shown and described.

DESCRIPTION

1. Battery tray
- 1.1 : Front
- 1.2 : Back
- 1.3 : Left side
- 1.4 : Right side
- 1.5 : Top
- 1.6 : Bottom
- 1.7 : Reference perspective view (front, top, right side)
- 1.8 : Reference top view
- 1.9 : Sectional view taken along line A-A
- 1.10 : Sectional view taken along line B-B

1 Claim, 10 Drawing Sheets(56)
